CRANKSHAFT GRINDING MACHINE

John I. Garside and Carl G. Flygare, Worcester,
Mass., assignors to Norton Company, Worcester,
Mass., a corporation of Massachusetts

Application March 26, 1937, Serial No. 133,222

17 Claims. (Cl. 51—72)

The invention relates to grinding machines, and more particularly to a machine for grinding cylindrical surfaces, such as crankshafts.

One object of the invention is to provide a simple, thoroughly practical grinding machine construction. Another object of the invention is to provide an improved electrical control mechanism for a grinding machine. Another object of the invention is to provide a grinding machine having an electrically actuated table traversing mechanism. Another object of the invention is to provide a grinding machine to provide a grinding machine having an electrically actuated grinding wheel traversing mechanism. Another object of the invention is to provide an improved grinding machine and control mechanism therefor in which the work table traversing mechanism, the wheel head traversing mechanism, the work rotating mechanism and the grinding wheel driving mechanism are all electrically controlled.

A further object of the invention is to provide a single control lever for controlling the longitudinal traversing movement of the table when moved in one direction and to control the transverse movement of the grinding wheel head when moved in another direction. A further object of the invention is to provide an improved interlock control mechanism for an electrically actuated table traverse mechanism and an electrically actuated wheel head traversing mechanism. Another object of the invention is to provide an interlocked electrical control mechanism whereby the rotation of the work, longitudinal traverse of the work table, transverse traverse of the grinding wheel slide and the movement of the work steady rest are all interlocked. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of the improved grinding machine, having parts broken away and shown in section more clearly to show the operating construction;

Fig. 2 is a right-hand end elevation, on an enlarged scale, of the improved crankpin grinding machine;

Fig. 3 is an electrical wiring diagram of the electrical control units of the machine;

Fig. 4 is a fragmentary rear elevation, on an enlarged scale, showing the wheel slide construction and the operating mechanism therefor;

Fig. 5 is a fragmentary plan view of the limit switch assembly and operating dogs for the wheel slide;

Fig. 6 is a side elevation of the limit switches and dogs for controlling the same, as shown in Fig. 5;

Fig. 7 is a fragmentary vertical sectional view, taken approximately on the line 7—7 of Fig. 4, showing the two-speed traversing mechanism for traversing the wheel slide;

Fig. 8 is a fragmentary vertical sectional view, on an enlarged scale, taken approximately on the line 8—8 of Fig. 2, through the control lever mechanism for the table and wheel units;

Fig. 9 is a fragmentary cross sectional view, taken approximately on the line 9—9 of Fig. 8;

Fig. 10 is a fragmentary cross sectional view, taken approximately on the line 10—10 of Fig. 8;

Fig. 11 is a vertical sectional view through the control lever mechanism, taken approximately on the line 11—11 of Fig. 8;

Fig. 12 is a fragmentary sectional view, taken approximately on the line 12—12 of Fig. 11;

Fig. 13 is a horizontal sectional view, taken approximately on the line 13—13 of Fig. 12;

Fig. 14 is a fragmentary perspective phantom view of the electrically driven table traversing mechanism;

Fig. 15 is a fragmentary sectional view, on an enlarged scale, through the work steady rest, taken approximately on the line 15—15 of Fig. 1;

Fig. 16 is a fragmentary vertical section through a portion of the steadyrest, taken approximately on the line 16—16 of Fig. 15; and

Fig. 17 is a fragmentary detail view of the cam and limit switch on the left-hand side of the steadyrest.

An improved grinding machine embodying this invention has been illustrated in the drawings, comprising a base 20 which supports a longitudinally movable work supporting table 21 which is arranged to slide longitudinally on a V-way 22 and a flat way 23 on the base 20. The work supporting table 21 supports a pair of opposed work supporting and rotating heads 24 and 25, each of which supports a rotatable work supporting spindle 26 and 27 carrying work holders 28 and 29, respectively. The work holders 28 and 29 are provided with work clamps 30 and 31 by which a work piece such as a crankshaft to be ground

may be clamped in an operating position on the machine. The details of the work clamping mechanism have not been illustrated, since this feature is not considered to be part of the present invention. These clamping members 30 and 31, as illustrated, are manually operable clamping members, such as for example that shown in the prior United States Patent to Norton No. 1,563,310 dated November 24, 1925, to 10 which reference may be had for a more complete disclosure of the work clamping mechanism.

The work spindles 26 and 27 are arranged so that they may be rotated in synchronism to rotate the opposite ends of a work piece, such as 15 a crankshaft 205. An electric motor 35 is adjustably mounted on the table 21 and is provided with a driving pulley 36 which is connected by a driving belt, such as multiple V-belts 37, with a pulley 38 which is mounted on the end of a shaft 20 39. The shaft 39 is journalled in a bearing 40 which is supported on the work head 24. The other end of the shaft 39 is provided with a splined portion 41 which meshes with an internally splined portion 42 in a rotatable hollow 25 shaft 43. The shaft 43 is journalled in bearings 44 and 45 carried by the work supporting heads 24 and 25, respectively. The hollow shaft 43 is provided with pulleys 46 and 47 which are slidably keyed to the hollow shaft 43 so as to facilitate 30 longitudinal adjustment of the work heads 24 and 25, respectively. The pulleys 46 and 47 are connected by driving belts 48 and 49 with pulleys 50 and 51, respectively, which are mounted on work rotating spindles 26 and 27. 35 The driving belts 48 and 49 are preferably of the multiple V-belt type comprising a plurality of driving belts of V-shaped cross-sectional area which ride upon multiple grooves in the pulleys 46—50 and 47—51, respectively. By providing 40 a drive as above described, a uniform driving torque is synchronously applied to each end of the work piece or crankshaft to be ground.

To facilitate grinding of crankshafts of different lengths, the work heads 24 and 25 are arranged to slide longitudinally on guiding and supporting surfaces 52 on the top of the work supporting table 21. The head 24 is provided with clamping members 53 and 54 and the head 25 is provided with clamping members 55 and 56, 50 by means of which the heads may be locked in adjusted position on the table 21.

A rotatable grinding wheel 60 is mounted on the outer end of a wheel spindle 61 which is rotatably journaled in a transversely movable 55 wheel slide 62. The other end of the wheel spindle 61 is provided with a driving pulley 63 which is connected by multiple V-belts 64 with a pulley 65 mounted on the outer end of a motor armature shaft 66 carried by an electric driving 60 motor 67 which is mounted on the upper surface of the wheel slide 62. The wheel slide 62 is preferably supported on a transversely movable intermediate slide 68. The wheel slide 62 is supported on a transversely extending V-way 69 65 and a flat way 70 on the intermediate slide 68. The intermediate slide 68 is in turn supported on a V-way 71 and a flat way 72 on the base 20 (Fig. 4).

The wheel slide 62 is arranged to be moved 70 transversely on the intermediate slide 68 by a power operated mechanism, to be hereinafter described, to move the wheel rapidly toward or from an operating position with relation to the work piece. The wheel 60 is arranged so that 75 it may be manually fed into the work piece to

grind the same to the required and predetermined size. This mechanism may comprise a manually operable wheel feeding mechanism of the type shown in the expired United States patent to C. H. Norton No. 762,838 dated June 14, 1904, to which reference may be had for a detailed disclosure thereof. The intermediate slide 68 is provided with a depending half nut 75 which meshes with or engages a rotatable cross feed screw 76 which is rotatably supported in suitable bearings (not shown) in the base 20. The feed screw 76 is connected to or formed integral with a shaft 77 which projects from the front of the machine base and is operatively connected to be rotated by a manually operable 15 feeding wheel 78.

The wheel slide 62 is provided with a power operated traversing mechanism which is arranged to move the slide first at a rapid rate to cause the grinding wheel 60 to approach the 20 work piece and then to reduce the approaching speed to a proper speed for grinding the cheeks or end faces adjacent to a crankpin, if desired. In the preferred form, an electric motor driven driving mechanism is provided for moving the 25 wheel slide 62 transversely relative to the intermediate slide 68 and the base 20. This mechanism comprises an electric motor 80 supported on a bracket 81 on the intermediate slide 68. The motor 80 is provided with a driving pulley 30 82 which is connected by a driving belt 83 with a pulley 84 mounted on the outer end of a rotatable shaft 85. The shaft 85 is journalled in a boss 86 projecting outwardly from a gear casing 87 which is fixed to the intermediate slide 68. 35 The inner end of the shaft 85 is provided with a gear 88 which meshes with a gear 89 supported on a shaft 90 which is rotatably journalled in bearings (not shown) in the casing 87. The gear 88 also meshes with a gear 91 supported on a 40 rotatable shaft 92 which is also mounted in bearings (not shown) in the casing 87. The shaft 90 supports a spiral gear 94 which is keyed 45 thereto to rotate therewith. The spiral gear 94 meshes with a spiral gear 95 rotatably supported on a shaft 96 which is supported in bearings 97 and 98, respectively, in the casing 87. The gear 95 is free to rotate on the shaft 96 when driven by the spiral gear 94. The shaft 92 is provided with a worm 99 meshing with a worm gear 100 which is rotatably supported on the 50 shaft 96. In order to transmit a rotary motion to the shaft 96, a movable clutch member 101 is slidably keyed thereto and is provided with clutch teeth at its opposite ends which are arranged to engage clutch teeth formed on the inner surface of the gear 95 or to engage a set of clutch teeth on the inner face of the worm gear 100 so that either the spiral gear 95 or the worm gear 100 may be locked by the clutch member 55 101 to rotate the shaft 96, either at a fast or a slow speed, as desired.

In order to shift the clutch member 101, a yoked member 102 is pivotally mounted on a stud 103 carried by the casing 87. An upwardly extending arm 104 is also supported on the stud 103 and is connected to move the yoked member 102. A spring 105 is connected between a stud 106 carried by the casing 87 and a stud 107 carried by the arm 104 and serves normally to 70 hold the clutch member 101 in engagement with the clutch teeth on the worm gear 100 to rotate the shaft 96 at a comparatively slow rate. In order to shift the clutch member 101 into engagement with the gear 95 to rotate the shaft 96 at a 75

comparatively rapid rate, an electric solenoid 108 is provided and supported on a bracket 109 which is fixed to or integral with the casing 87. The armature 110 of the solenoid 108 is connected by a screw 111 and a stud 112 with the upper end of the arm 104 and is arranged so that when the solenoid is energized, the arm 104 and yoke 102 are rocked in a clockwise direction (Fig. 7) to shift the clutch member 101 into engagement with the clutch teeth on the gear 95 to rotate the shaft 96 at a comparatively rapid rate.

The outer end of the shaft 96 is provided with a sprocket 115 which is connected by a link chain 116 with a sprocket 117 mounted on the outer end of a rotatable feed screw 118 which is journaled in suitable bearings (not shown) in the intermediate slide 68. A half nut 119 depends from the wheel slide 62 and engages or meshes with the feed screw 118 so that when the feed screw 20 118 is rotated by the gear mechanism above described, the wheel slide 62 will be moved transversely to cause the wheel 60 to approach or recede from the work piece being ground either at a fast or at a slow speed. In order to maintain the desired driving tension on the link chain 116, an idler sprocket 120 is rotatably mounted on a stud 121 carried by an idler bracket 122 which is pivotally supported on a stud 123 fixed to the rear of the intermediate slide 68. A clamping screw 124 passes through an elongated slot 125 in the idler bracket 122 and is screw threaded into the end of the intermediate slide 68. By manipulation of the screw 124, the idler bracket 122 may be swung to take up the slack 30 in the driving chain 116 and then locked in adjusted position.

To facilitate an interlocking of the various mechanisms of the machine and controlling the electrical circuits therefor, a series of electrical switches, such as limit switches 130, 131, 132 and 133 are mounted on the upper surface of the casing 87 which is carried by the intermediate slide 68. A plate 135 fixed to the wheel slide 62 carries a plurality of adjustable dog bars which are arranged to engage and actuate the normally closed limit switches 130, 131, 132 and 133. The limit switches and dogs are staggered and spaced from each other so that they may be operated at the desired time during the movement of the wheel slide 62 toward and from the work piece. An adjustable dog 136 is adjustably mounted on the plate 135 by means of a screw 137 which passes through an elongated slot 138 in the plate 135. The dog 136 is arranged to engage and actuate the normally closed limit switch 133. A dog bar or plate 139 is adjustably secured to the plate 135 by means of a screw 140 passing through an elongated slot 141. The dog bar or plate 139 is arranged in the path of the limit switch 132 so as to actuate the switch in the desired timed relationship with the movement of the wheel slide 62. A dog 142 is adjustably secured to the plate 135 by means of a screw 143 which passes through an elongated slot 144 to facilitate adjustment of the dog 142 relative to the limit switch 131 so as to actuate the same in the desired time during the movement of the wheel slide 62. A similar dog 145 is held in adjusted position on the plate 135 by means of a screw 146 which passes through an elongated slot 147. The dog 145 is arranged in the path of the limit switch 130 so as to actuate the switch when the wheel slide 62 is moved. The operation of the limit switches above described, together with their inter-connection with

the various mechanisms of the machine, will be described hereinafter.

The work table 21 is arranged so that it may be traversed either manually or by power. A manually operable traverse mechanism is provided including a manually operable hand wheel 155 which is connected through a gear mechanism (not shown) with a rack bar 156 depending from the table 21. The manually operable traverse mechanism is not considered to be part of the present invention and consequently has not been illustrated in detail. This mechanism may be arranged substantially as shown in the prior expired patent to Norton No. 762,838 dated June 14, 1904, to which reference may be had for a more detailed disclosure of the manual traverse mechanism.

Power traverse—work table

It is desirable to provide a power operated traverse mechanism which is preferably arranged so that the work supporting table 21 may be traversed rapidly to position various portions of the crankshaft 205 in operative relation with the grinding wheel 60, or moved at a relatively slow rate in either direction for truing the grinding wheel 60. An electrically driven mechanism is provided comprising a reversible electric motor 157 (Figs. 2, 3 and 14) which is supported on the rear of the base 20 of the machine. An armature shaft 158 (Fig. 14) of the motor is provided with a pulley 159 which is connected by a driving belt 160 with a pulley 161 mounted on the end of a rotatable shaft 162. A gear 163 is either fixed to or formed integral with the shaft 162. A movable clutch member 164 is slidably keyed to a rotatable shaft 165. The clutch member 164 is arranged so that it may be moved by means of a yoked member 166 which is mounted on one end of a shaft 167. A lever 168 and a link 169 serve to rock the yoked member 166 to shift the movable clutch member 164 when desired. When the clutch member 164 is thrown into engagement with a set of clutch teeth 170, which are formed integral with the shaft 162 and gear 163, a rotary motion is transmitted to the shaft 165.

Rapid table traverse

The other end of the shaft 165 carries a gear 175 which meshes with a gear 176 supported on the end of a rotatable shaft 177. The shaft 177 carries a worm 178 meshing with a worm wheel 179 which is rotatably mounted on a shaft 180. The shaft 180 carries a gear 181 meshing with a gear 182 which is rotatably supported on a shaft 183. The shaft 183 supports a gear 184 which meshes with a large gear 185 mounted on the end of a shaft 186. The shaft 186 is provided with a driving pinion 187 which meshes with the rack bar 156 depending from the table 21, so that when the clutch member 164 is thrown into engagement with the clutch teeth 170, the rotary motion transmitted from the reversible electric motor 157 is transmitted through the gear mechanism, above described, to the rack bar 156 to traverse the table 21 longitudinally at a relatively rapid rate.

Slow table traverse

In order to obtain a slow movement of the table for a truing operation, a reduction gear mechanism is provided comprising a gear 195 which meshes with the gear 163 and is supported on a rotatable shaft 196. The shaft 196 supports a worm 197 meshing with a worm gear 198 mounted on a rotatable shaft 199. The shaft 199 car-

ries a worm 200 which meshes with a worm gear 201 rotatably supported on the shaft 165. The gear 201 is provided with clutch teeth 202 which are arranged to be engaged by the movable clutch member 164. When a slow traverse of the table 21 is desired, the yoked member 166 is rocked in a clockwise direction to move the clutch member 164 toward the left (Fig. 14) so that it engages the clutch teeth 202 carried by the gear 201. Power from the reversible motor 157 is then transmitted through the gear 163, the gear 195, the shaft 196, the worm 197, the worm gear 198, the shaft 199, the worm 200, the worm gear 201, the clutch teeth 202, to rotate the clutch member 164 and the shaft 165 to transmit a rotary motion to the gear mechanism 175 to 187 inclusive to transmit a slow traversing movement to the rack bar 156 and the table 21.

Steadyrest

The work piece, such as the crankpin 205 being ground, is preferably steadied by a steadyrest 206 having a downwardly extending frame 207 which is fixedly mounted on the front of the machine base 20. The steadyrest frame 207 is arranged to support a movable steadyrest slide 208 which may be moved into and out of an operative position by means of a handle 209. The slide 208 carries a pivotally mounted steadyrest shoe 210 which is arranged to engage the under side of the work piece 205 at a point adjacent to the line of contact between the work piece 205 and the operative face of the grinding wheel 60. The frame 208 also supports a horizontally movable steadyrest shoe 211 which is arranged to engage the work piece at a point diametrically opposite the line of contact between the grinding wheel 60 and the work piece 205.

The lower steadyrest shoe 210 is pivotally mounted on a stud 212 carried by the slide 208. The steadyrest shoe 210 is held in an upward position by means of a link 213 which is connected by a stud 214 with the shoe carrying member and is connected by a stud 215 with a slide block 216 which is actuated by a rod 217. The rod 217 may be precisely adjusted to maintain the steadyrest shoe 210 in supporting engagement with the work by means of a knob 218 which is threaded onto a screw threaded portion 219 of the rod 217. To facilitate rapid removal of the lower shoe 210 from engagement with the work, a quick acting sleeve 220 supports the outer end of the rod 217 and is arranged so that when rotated by a handle 221 through a quarter turn, it may be rapidly withdrawn toward the left (Fig. 15) rapidly to slide the rod 217 and drop the work steadyng shoe from operative engagement with the work piece 205. The work steadyng shoe 211 is carried by a transversely movable slide 225 which is supported in the slide 208 and is adjusted relative thereto by means of a nut 226 and a screw 227.

The steadyrest slide 208 is arranged so that it may be rapidly moved to and from an operating position. As illustrated in Fig. 15, a spring pressed locating plunger 230 engages a locating aperture in the under side of the slide 208 and serves to hold the slide in an operating position during a grinding operation. When it is desired to traverse the table 21 or to remove a work piece 205 from the machine, the locating plunger 230 may be rapidly withdrawn from the notch in the slide 208 by raising the lever 231 and then pulling the handle 209 to withdraw the steadyrest to an inoperative position.

In the present machine, the work rest is of a massive construction and requires considerable effort on the part of the operator manually to withdraw the same by means of the handle 209. To facilitate movement of the steadyrest to an inoperative position, a rack and gear mechanism is provided. A rack bar 235 is mounted on the slide 208. A gear 236 is mounted on a rotatable shaft 237 and meshes with the rack bar 235. The shaft 237 is journaled in suitable bearings in the steadyrest frame 207. A crank handle or lever 238 (Figs. 2 and 16) is mounted on the outer end of the shaft 237 and is arranged so that by manipulation of the lever 238, the steadyrest slide 208 may be readily moved to and from an operative position without undue exertion on the part of the operator.

Interlock—steadyrest and table traverse

It is desirable in a machine of this type to provide suitable interlocks between the various mechanisms of the machine to insure safe operation thereof. It is desirable to provide an interlock between the steadyrest and the table traverse mechanism which is so arranged that the table 21 cannot be traversed when the steadyrest is in a forward or operating position. To accomplish this result, a normally open limit switch 240 is mounted on a bracket 241 on the left-hand side of the steadyrest casing (Fig. 16). When the steadyrest is in a forward position, as indicated in Fig. 16, the limit switch 240 remains open, thereby causing a break in a circuit which controls the table traverse mechanism, so that the table movement cannot be started. A cam 242 is mounted on the end of the shaft 237 and is arranged so that when the lever 238 controlling the movement of the steadyrest is turned to withdraw the steadyrest to an inoperative position, the cam 240 swings into the position illustrated in Fig. 17 to close the limit switch 240 so that the table may then be traversed by manipulation of the table traverse control lever. This mechanism serves to prevent accidental starting of the table traverse when the work steadyrest and shoes are in an operating position between the crank arms of a crankshaft 205.

Interlock—work rotation and steadyrest

It is also desirable to provide an interlock between the work rotation and the steadyrest, so that the work piece or crankshaft cannot be rotated unless the steadyrest is in a forward or operating position. A limit switch 245 is mounted within the steadyrest casing 207. The roller 246 of the limit switch 245 is arranged in the path of a head 247 on the lower end of the locating plunger 230, so that when the lever 231 is lifted to withdraw the locating plunger 230 so that the rest may be withdrawn to an inoperative position, the head 247 of the plunger 230 engages the limit switch roller 246 and opens the limit switch 245, thereby breaking a circuit to the headstock or work driving motor 35 to prevent rotation thereof during the time the rest is in a rearward or inoperative position.

Main control lever

It is desirable to provide a single main control lever which is operatively connected and arranged so that when the lever is moved into various control positions, the movement of the table may be controlled to traverse the table in either direction at a comparatively rapid rate to position the work piece in operative relation with the grinding wheel or may be moved at a slow

rate for truing the grinding wheel. The control lever is also arranged so that when moved into a different position, the lever will control the forward and reverse feeding movement of the grinding wheel. A main control lever 250 is slidably and rotatably mounted within a sleeve 251 (Figs. 8 and 11) which is pivotally supported on a yoked member 252 by means of a stud 253 which passes through the two arms of the yoke 252 and through an enlarged portion of the sleeve 251. This pivotal connection serves to permit the control lever 250 to be rocked toward and from the machine. The yoked member 252 is provided with a horizontally extending stud or trunnion 254 (Fig. 11) which is journaled in a bearing 255 so that the lever 250 may be rocked sideways in either direction. The bearing 255 is formed as an integral part of a control apron 256 which is fastened to the front of the machine base 20. A cover plate 257 on the apron 256 is provided with an H-shaped opening 258 (Fig. 10) which serves to control the in and out and sidewise movement of the control lever 250.

The control lever 250 comprises a central rod 260, the lower end of which is supported in a bearing 261 in the sleeve 251. A sleeve 262 surrounds the upper portion of the rod 260 and is supported in a bearing 263 carried by the sleeve 251. A spring 264 surrounds the rod 260 and is contained within an enlarged aperture within the sleeve 251 and is interposed between a shoulder at the bottom of the enlarged hole within the sleeve 251 and the end of the sleeve 262 and serves normally to hold the sleeve 262 and rod 260 in its uppermost position. The lever 250 has been shown in its central or neutral position (Figs. 8, 10 and 11).

The sleeve 251 is provided with two rearwardly extending lugs 266 and 267 which support a rod 268. The yoked member 269 is supported by a pair of slidably mounted rods 271 and 272 (Figs. 11 and 12) which are slidably supported in bearings 273 and 274 in the apron 256. The slide rods 271 and 272 serve to support a member 275 having a track cam 276 formed in its lower surface. The member 275 is mounted and supported on the base slide rods 271 and 272 and has its opposite ends slotted and provided with clamping screws 280 and 281 by means of which the member 275 may be clamped in adjusted position on the rods 271 and 272. A follower 282 (Figs. 11 and 12) engages the cam track 276 and is formed on the upper end of a lever 283 supported on one end of a rotatable shaft 284 which is journaled in a bearing member 285 in the apron 256. The other end of the shaft 284 is provided with a downwardly extending lever 286 which is connected by a stud 287 with a yoked end 288 of the connecting link 169 which is connected to actuate the clutch member 164.

When the control lever 250 is moved in a clockwise direction (Fig. 11) about the pivot 253 into position 250a (Fig. 10), the rod 268, yoke member 269 and rods 271 and 272 serve to move the cam member 275 toward the right (Fig. 11) which in turn serves to rock the follower 282 and the lever 283 in a clockwise direction (Fig. 12) which serves through the link 169 to shift the clutch member 164 toward the right (Fig. 14) into engagement with the clutch teeth 170 so as to transmit power from the table traverse motor 157 through the gear mechanism above described to traverse the table 21 at a comparatively rapid rate.

The electric motor 157 is a reversible type mo-

tor which is controlled by a reverse starter switch 290 which is mounted within the apron 256. The pivotally mounted trunnion or stud 255 supports a downwardly extending lever 291 (Fig. 11) which is provided with a yoked portion 292 at its lower end. The yoked portion 292 straddles a pin or stud 293 which is carried at the lower end of a lever 294. The lever 294 is mounted on a rotary shaft 295 which actuates the reverse starter switch 290. The reversing switch 290 operates through a magnetic starter reversing switch 296 (Fig. 3) to control the rotation of the motor 157 and thereby to control the direction of movement of the work supporting table 21. When the control lever 250 is moved from position 250a into position 250b, the control lever is rocked in a counterclockwise direction (Fig. 8) which serves through the trunnion 255 and lever 291 to shift the reversing switch 290 from a central or neutral position to operate through the starter switch 296 to start the motor 157 rotating in one direction to transmit a corresponding traversing movement to the table 21 toward the left. If it is desired to move the table in the reverse direction, the control lever 250 may be shifted from position 250b into position 250c, which operates to shift the reversing switch 290 into a reverse position, thereby shifting the magnetic starter switch 296 to reverse the flow of current to the motor 157 and to start the table traversing toward the right.

When it is desired to move the table at a slow rate in either direction for truing the grinding wheel, the control lever 250 is moved into position 250d which serves through the rod 268 (Fig. 11), the yoke 269, the rods 271 and 272, and the cam member 275, to shift the levers 283 and 286 and thereby shift the clutch member 164 into engagement with the clutch teeth 170, so that power from the motor 157 is transmitted through the slow speed gearing above described to traverse the table 21 at a comparatively slow rate of speed. The movement of the control lever 250 from position 250d into position 250e serves to actuate the reversing switch 290 to start the table traversing slowly in a direction toward the left. Similarly, movement of the control lever 250 from position 250e or 250d into position 250f serves to start the table moving slowly in a direction toward the right. It will be readily apparent from the foregoing disclosure that by shifting the control lever 250 within the H-shaped aperture 258, the work supporting table 21 may be traversed in either direction, either at a comparatively fast or at a comparatively slow rate of speed. The direction of movement of the lever 250 within the H-shaped slot determines the direction and speed of movement of the table. The lever 250 is moved in the direction it is desired to traverse the table.

Wheel feed control

It is desirable to provide a suitable mechanical interlock between the electrical table traverse and the electrical wheel slide movements so that the table cannot be traversed when the wheel slide is being moved. It is, therefore, desirable to provide a further control movement of the lever 250 to operate the wheel feeding movement and at the same time prevent movement of the table 21. This is preferably accomplished when the control lever is in the center part of the H-shaped slot in the cover plate 257.

In order to control the infeeding movement of the grinding wheel 60, a reversing switch 300 (Fig. 11) is mounted within the apron 256 and is connected through a magnetic reverse starter 75

switch 301 to control the wheel slide motor 80 to cause either a forward or rearward movement of the wheel slide 62. The reversing switch 300 is provided with a control shaft 302. A gear segment 303 is mounted on the upper end of the shaft 302 and meshes with a gear segment 304 which is formed integral with a rotatable stud 305 which is journaled in a bearing 306 in the apron 256. The stud 305 is provided with a central aperture 307 and its upper surface is provided with a transversely extending slot 308 (Figs. 8, 9 and 11).

The lower end of the sleeve 251 supports a bushing 310 which is keyed thereto and clamped in place therein by means of a clamping screw 311 which passes through a pair of opposed lugs 312 in a split portion formed at the lower end of the sleeve 251. The bushing 310 is provided with a pair of downwardly extending portions 313 and 314 (Fig. 8) which serve as a guide normally to prevent rotation of an elongated key member 315 formed integral with the lower end of the rod 260. A stud 316 is also formed integral with the key member 315 and the rod 260.

When the control lever 250 is in a central position 250 within the H-shaped slot 258 (Fig. 10), a feeding movement of the wheel slide may be obtained by pushing downwardly on the control lever 250 against the tension of the spring 264. This movement serves to move the stud 316 downwardly into engagement with the hole 307 in the rotatable stud 305 and also serves to move the key member 315 downwardly into engagement 35 with the transversely extending slot 308 in the gear segment member 304. In this position of the parts, the control lever 250 and rod 260 may be rotated by means of a crank arm 317. Movement of the crank arm 317 serves through the key 315 40 to move the gear segment 304, which transmits a corresponding movement of the gear segment 303 to shift the reversing switch 300, which operates through the magnetic starter reversing switch 301 to control the motor 80 to cause either a forward or rearward movement of the wheel slide 62. The reversing switch 300 is preferably arranged 45 so that the wheel slide 62 will be moved in the direction in which the crank arm 317 is moved, that is, when the crank arm 317 is moved toward the rear of the machine, the wheel slide 62 will be moved rearwardly, or when the crank arm 317 is moved forwardly toward the operator, the wheel slide 62 and motor 80 will be rotated to cause a forward approaching movement of the grinding wheel 60 and the wheel slide 62. The stud 316 50 engaging the hole 307 during the movement of the wheel slide 62 prevents the lever 250 from being shifted from its central position, thereby locking the control lever 250 so as to prevent a traversing movement of the table during the forward or rearward movement of the wheel slide 62.

During the normal operation of the machine, the limit switch 132 which is supported on the intermediate wheel slide 68 serves to prevent table traverse when the wheel slide 62 is in a forward position. In order that the grinding wheel 60 may be trued when desired, it is desirable to provide a means for allowing a slow traversing movement of the work table when the wheel slide is in its forward position. To accomplish this result, a normally open limit switch 320 is mounted within the apron 256 and is connected in parallel with the limit switch 132. The switch 320 has a roller 321 which is arranged in 75 the path of a cam 322 formed on the upper sur-

face of the slide block 275 so that when the block 275 is moved toward the left (Fig. 11) as the control lever 250 is moved forward into a low speed position, the normally open limit switch 320 is closed, thereby closing the circuit (while the limit switch 132 remains open) so that the wheel slide 62 will remain in the forward position during a slow traversing speed of the table 21 while truing the grinding wheel.

When the wheel slide 62 is moved forward into a grinding position, the movement starts at a rapid rate, which continues until the dog 142 engages and opens the limit switch 131, thereby deenergizing the solenoid 108 to release the tension of the spring 105, which shifts the clutch member 101 into a slow speed position to cause a slow forward advancing movement of the grinding wheel. The slow power infeed of the grinding wheel is preferably of a suitable rate for the grinding of the cheeks adjacent to the ends of a crankpin.

The slow power infeed of the wheel slide 62 continues until the dog 136 actuates the limit switch 133, thereby breaking the circuit which serves through the magnetic switch 301 to stop the rotation of the wheel feed motor 80. The dog 136 is preferably so adjusted that slow power infeed is stopped just before the periphery of the grinding wheel 60 engages the cylindrical body of the crankpin to be ground. The body or cylindrical pin may then be ground by manually advancing the grinding wheel 60 by rotation of the manually operable feed wheel 78. The crankpin may be accurately ground to a predetermined size by manipulation of the manually operable feed wheel.

After a grinding operation has been completed, it is desirable to provide a suitable control so that the grinding wheel slide 62 may be moved rapidly to its rearward position. This is preferably accomplished by means of a normally open limit switch 325 mounted within the control apron 256 and connected in parallel with the limit switch 131 to actuate the solenoid 108. The limit switch 325 is provided with an actuating roller 326 arranged in the path of a cam surface 327 formed integral with the gear segment 304. The limit switch 325, which is normally open, is shunted across the circuit so that when the lever 317 is moved rearwardly to shift the reversing switch 300 to reverse the direction of rotation of the motor 80 to cause a rearward movement of the wheel slide 62, the solenoid 108 is energized instantaneously to shift the clutch member 101 into a high speed position rapidly to withdraw the wheel slide 62 and grinding wheel 60 to an inoperative position.

It is desirable to provide a control mechanism to prevent the table 21 traversing beyond the desired extent to prevent the work supporting heads 28 and 29 from being traversed into the grinding wheel. A pair of limit switches 329 and 330 (Fig. 3) are mounted on the front of the steadyrest frame 206 within a casing 331 (Fig. 15) and are provided with actuating rods 332 and 333 which are arranged to be engaged by lugs 334 and 335 carried by the work heads 24 and 25, respectively. The limit switches 329 and 330 are normally closed and are connected so that when the rod 332 or the rod 333 engages the lug 334 or the lug 335, respectively, to open one or the other of the limit switches 329 or 330, it breaks the circuit, thereby to open the magnetic starter switch 296 to stop the rotation of the table trav- 75

erse motor 157 before the wheel 60 engages either of the work supporting heads 28 or 29.

Electrical control station

The electrical wiring diagram has been illustrated in Fig. 3, showing the electrical diagram for controlling the various operating units on the machine. It is desirable to provide a central control station whereby the various operating units on the machine may be readily controlled within easy reach of the operator. A series of control push buttons are preferably mounted on the side of the steadyrest casing within easy reach of the operator. Referring now to Figs. 2 and 3, a push button control 336 is arranged to control the stopping and starting of the wheel rotating motor 61. When the push button 337 is pushed in, a circuit is made to operate a magnetic starter switch 338 to start the rotation of the motor 61. Similarly, pushing in on the button 339 serves to break the circuit, thereby operating the magnetic switch 338 to stop the rotation of the wheel driving motor 61. A push button switch 340 serves to control a magnetic switch 341 to stop and start a motor 342 for rotating a coolant fluid pump (not shown). Pushing in on a button 343 serves to operate the magnetic switch 341 to stop the rotation of the motor 342. Similarly, pushing in on the button 344 serves through the magnetic starter switch to start the rotation of the coolant fluid motor 342.

A push button switch 345 having a push button 346 serves as a jogging switch to operate through the magnetic switch 296 to inch or jog the motor 157 to cause the table 21 to move longitudinally by short increments. This switch serves instantaneously to close the magnetic switch 296, which serves to traverse the table through a very small extent to position the work piece in operative relation with the grinding wheel 60. A push button switch 347 having a stop push button 348, an inch or jog button 349, and a run button 350 serves to control the rotation of the motor 35 for rotating the work head and crankshaft being ground. Pushing in on the stop button 348 serves to open a circuit, deenergizing a work stop solenoid 351, which operates through a trip switch 352 and a magnetic switch 353 to stop the rotation of the motor 35. The work stop control mechanism for stopping the rotation of the motor 35 so that the work heads are always in an upright or vertical position is not considered part of the present invention, consequently the details of construction and the controls have not been illustrated.

The work rotation motor 35 may be jogged or inched, if desired, by pushing the button 349 which operates through a solenoid relay 354 instantaneously to operate the magnetic switch 353 to inch or jog the rotation of the motor 35 and the work supporting heads 30 and 31, respectively. Pushing in on the button 350 closes a circuit and operates through the solenoid switch 354 to operate the magnetic switch 353 and continuously rotate the motor 35 and the work supporting heads 30 and 31 during the grinding operation.

It will be readily apparent from the foregoing description of the controls that the operator may, from a single position in front of the machine, actuate not only the main control lever but also control the starting and stopping of jogging of the various motors on the machine.

The operation of this machine will be readily apparent from the foregoing disclosure. A work piece, such as a crankshaft 205, is placed in posi-

tion on the work heads 28 and 29 and clamped in position thereon by the clamping members 30 and 31, respectively. The steadyrest lever 238 is then pushed forward to position the steadyrest slide 208 in an operating position with the locating plunger 230 in the position as illustrated in Fig. 15. The control lever 250 is then moved in a clockwise direction (Fig. 11) into position 250a (Fig. 10) and then shifted either into position 250b or 250c to move the table 21 longitudinally to position a crankpin in operative position opposite the operative face of the grinding wheel 60. When the crankpin reaches a predetermined position, the control lever 250 is shifted from position 250b or 250c through the position 250a into position 250, as shown in Figs. 8, 10 and 11. The operator then pushes the button 337 to start the rotation of the motor 61 and the grinding wheel 60 and then pushes the button 350 to start rotation of the work drive motor 35 synchronously to rotate the work supporting heads 28 and 29 and the crankshaft 205. The lever 250 is then pushed downwardly so that the stud 316 engages the hole 307 in the rotatable stud 305 and the key 315 engages the slot 308, after which the lever 317 is pulled toward the operator to start a rapid forward movement of the grinding wheel 60 and the wheel slide 62. The rapid approaching movement of the wheel slide 62 continues until the dog 142 engages and actuates the limit switch 131 to break the circuit and deenergize the solenoid 108 to release the tension of the spring 105 and shift the clutch member 101 toward the right (Fig. 7) into a slow speed position. During the rapid approaching movement of the grinding wheel, a manually operable hand wheel 360 may be rotated to operate a spark splitting device, that is to shift the grinding wheel spindle 61 axially in either direction precisely to locate the grinding wheel 60 relative to the crankpin to be ground, so that when the rapid approach is reduced to a slow approaching feed of the grinding wheel, the side grinding of the wheel on the cheeks of a crankpin will be equalized. The power approaching feed of the wheel at a slow rate continues until the dog 136 actuates the limit switch 133 to open a circuit, thereby releasing one side of the magnetic switch 301 to stop the rotation of the wheel feed motor 80. The body of the crankpin may then be ground to the desired extent by manual rotation of the feed wheel 78. During the initial grinding of a crankpin 205, the work steadyrest shoes 210 and 211 remain out of contact with the pin to allow the grinding wheel 60 to rough grind and round up the pin. After a preliminary grinding on the pin, the operator moves the steadyrest shoes 210 and 211 into an operating position (Fig. 15) and thereafter manually adjusts the shoes 210 and 211 by actuating the knobs 218 and 226, respectively, during the grinding operation as the pin is ground to size.

After the pin has reached the desired size, the lever 250 being in a downward position, the lever 317 moves away from the operator, which serves to start the rotation of the motor 80 in the reverse direction and, through the electrical switches and circuits above described, serves to cause a rapid rearward movement of the wheel slide 62 to remove the grinding wheel 60 to its rearward or inoperative position. The lever 231 of the steadyrest is then raised to withdraw the locating plunger 230, and the steadyrest slide 208 is withdrawn by actuating the lever 238, after which the control lever 250 is allowed to move

upwardly to withdraw the pin 316 from the hole 307 so that the lever 250 may be again shifted through position 250a into position 250b or 250c to traverse the work supporting table 21 longitudinally to position the next crankpin in operative position opposite the operative face of the grinding wheel 60. The infeed and sizing of the pin are then controlled in the manner above described. After all of the pins which are in axial alignment have been found, the push button 348 may then be pushed to operate through the control switches above described to stop the rotation of the work drive motor 35 with the work holders 28 and 29 in an upright or vertical position, after which the clamping members 30 and 31 may be released and the crankshaft 205 indexed to bring the next set of crankpins into axial alignment with the work rotating and supporting spindles 26 and 27, after which the clamps 30 and 31 secure the crankshaft 205 in position and the cycle of operation is continued by traversing the table 21 and feeding the wheel 60 until all of the crankpins on the shaft have been ground to the required and predetermined size.

To facilitate accurate positioning of the table 21, a jogging button 346 is provided which serves to jog or inch the motor 151 precisely to locate the table 21 relative to the grinding wheel 60. Similarly, a jogging button 349 is provided to permit jogging or inching the work rotating motor 35 in setting up the machine for grinding a particular crankpin, so that the operator may be sure that the table 21 is in a position so that the crank arms clear the side face of the grinding wheel 60 before the work 205 is set in continuous rotation for a grinding operation.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

We claim:—

1. A crankpin grinding machine having a transversely movable wheel slide, a longitudinally traversable work table, each of which is operated by a separate reversible electric motor, a separate reversing switch operatively connected to control each of said motors, a single manually operable main control lever, and connections between said reversing switches and the main control lever whereby either the work table or the wheel slide motor is rendered inoperative during the operation of the other member.
2. In a grinding machine, a rotatable grinding wheel, a transversely movable slide therefor, means including a reversible motor to move said slide in either direction, a multi-speed gear mechanism including a clutch interposed between the motor and slide and arranged to move the slide at any one of said speeds, a solenoid to actuate said clutch, a manually operable reversing switch to control said motor, and means including an electric switch actuated by movement of said slide to control said solenoid and clutch to change the rate of movement of the slide.
3. In a grinding machine, a rotatable grinding wheel, a transversely movable slide therefor, means including a nut and screw mechanism to move said slide, means including a reversible elec-

tric motor to rotate said feed screw in either direction, a two-speed gear mechanism including a clutch interposed between the motor and feed screw and arranged to rotate the feed screw at either of said speeds, a solenoid to actuate said clutch, a manually operable reversing switch to control said motor, means including a limit switch to control said solenoid and clutch to change the rate of movement of the slide, and an adjustable cam on said slide to actuate said switch.

4. In a grinding machine, a rotatable grinding wheel, a transversely movable slide therefor, means including a rotatable screw and a nut to move said slide in either direction, a two-speed gear mechanism including a clutch to rotate said feed screw at either of two speeds, means including a reversible electric motor to transmit power to said gear mechanism, a manually operable reversing switch to control said motor, means normally to hold said clutch in a low speed position, a solenoid to shift said clutch into a high speed position, and means including a limit switch and a dog to control said solenoid so that the grinding wheel may be caused to move rapidly in one direction until the slide has reached a predetermined point and to move thereafter at a slower rate.

5. In a grinding machine, a rotatable grinding wheel, a transversely movable slide therefor, a rotatable work support, a longitudinally movable table therefor, means including a rack and gear to traverse said table, means including a reversible electric motor to rotate said gear in either direction, a two-speed gear mechanism including a clutch interposed between the motor and rack and gear which is arranged to rotate said gear and traverse said rack and table at either of two speeds, a reversing switch to control said motor, and a manually operable control lever which is operatively connected to actuate said clutch when moved in one direction and to actuate said reversing switch when moved in another direction.

6. In a grinding machine, a rotatable grinding wheel, a transversely movable slide therefor, a two-speed gear mechanism including a clutch to move said slide transversely in either direction, means to move and normally to hold said clutch in a slow speed position, a solenoid to move said clutch into a high speed position, a reversible electric motor to drive said gear mechanism, a magnetic reverse starter switch therefor, a manually operable reversing switch, and a normally closed limit switch which is opened after a predetermined fast approaching movement of the slide to actuate said solenoid and thereby reduce the rapid approaching feed to a slow feed.

7. In a grinding machine having a rotatable grinding wheel, a transversely movable slide therefor, a two-speed gear mechanism including a clutch to traverse said slide in either direction, a reversible electric motor to drive said gear mechanism, a reversing switch therefor, means to move and normally to hold said clutch in a slow speed position, and a solenoid to move said clutch to a high speed position, and a pair of spaced limit switches which are connected in series with said magnetic reverse starter switch to stop the wheel slide motor and prevent overrun on the forward and rearward movement of the slide.

8. In a grinding machine, a rotatable grinding wheel, a transversely movable slide therefor, means including a rotatable screw and a nut to move said slide in either direction, a two-speed gear mechanism including a clutch to rotate said feed screw at either of two speeds, means includ-

ing a reversible electric motor to actuate said gear mechanism, means normally to hold said clutch in a low speed position, a solenoid to shift said clutch into a high speed position, a manually operable reversing switch to start said motor in either direction, a limit switch and an adjustable cam for actuating said limit switch which are interposed between the base and slide, said limit switch being arranged to operate a circuit after the 10 wheel has moved rapidly toward a work piece to actuate said solenoid and shift the clutch into a slow speed position to cause a slow movement of said wheel and slide.

9. In a grinding machine having a base, a rotatable grinding wheel, a transversely movable slide to support said wheel, means including a reversible electric motor which is operatively connected to move said slide in either direction to position the grinding wheel adjacent to the work 20 piece or to move the same to an inoperative or rearward position, an intermediate slide supporting said reversible motor, a manually operable nut and screw mechanism interposed between the intermediate slide and base whereby the grinding wheel may be manually fed into the work, a reversing switch to control said motor, a longitudinally movable work supporting table, means including a manually operable lever to control the direction of movement of the table, and connections between said lever and said reversing switch whereby movement of the control lever in one direction serves to actuate the reversing switch and thereby control the transverse movement of said grinding wheel slide.

35 10. In a grinding machine having a rotatable grinding wheel, a transversely movable slide therefor, means including a reversible electric motor to feed said slide, a longitudinally movable work supporting table, a two-speed gear mechanism including a clutch to traverse said table, a reversible electric motor to drive said gear mechanism, a magnetic reverse starter switch therefor, a reversing switch for controlling the reverse starter switch and motor, a limit switch, means to actuate said limit switch by and in timed relation with the forward movement of said wheel slide normally to render said table traversing motor inoperative during the infeeding movement of the grinding wheel, and a second limit switch 45 connected in parallel with the first limit switch which is actuated by and in timed relation with the movement of said clutch to a slow speed position to close a circuit to permit the wheel slide to remain in a forward position during a slow truing 50 speed of the work table.

55 11. In a grinding machine having a longitudinally movable work supporting table, means including a reversible electric motor to traverse said table in either direction, a reversing switch therefor, a rotatable grinding wheel, a transversely movable slide therefor, means including a reversible electric motor to traverse said wheel slide in either direction, a reversing switch therefor, and a limit switch actuated by the forward movement of said slide to break a circuit and render the table traverse motor inoperative during the infeeding movement of the wheel slide.

60 12. In a grinding machine having a longitudinally movable work supporting table, a reversible motor to traverse said table in either direction, a reversing switch therefor, a rotatable work support on said table, an electric motor to rotate said work support, a rotatable grinding wheel, a transversely movable slide therefor, means including a reversible electric motor to traverse said slide

in either direction, a reversing switch therefor, a steadyrest which is movable to and from an operating position, and a limit switch which is operated when the steadyrest is moved to an inoperative position to break a circuit and prevent rotation of the work drive motor.

13. In a grinding machine having a longitudinally movable work supporting table, a reversible motor to traverse said table in either direction, a reversing switch therefor, a rotatable work support on said table, an electric motor to rotate said work support, a rotatable grinding wheel, a transversely movable slide therefor, means including a reversible electric motor to traverse said slide in either direction, a reversing switch therefor, a steadyrest which is movable to and from an operating position, and a limit switch which is actuated by the steadyrest when the steadyrest is moved to an operative position to open a circuit so as to prevent rotation of the table drive motor when the steadyrest is in an operative position.

14. In a grinding machine, a rotatable grinding wheel, a transversely movable wheel slide to support said wheel, means including a reversible electric motor to move said slide in either direction, a longitudinally movable work supporting table, means including a gear mechanism and a clutch to move said table at either of two speeds, means including a reversible electric motor to rotate said clutch and gear mechanism, a reversing switch operatively connected to reverse said motor and gearing, a manually operable control lever, connections between said control lever and said clutch whereby movement of said lever in one direction serves to shift the clutch to change the table speed, and connections between said lever and reversing switch whereby movement of said lever in a second direction serves to actuate the reversing switch and thereby to control the direction of movement of said table.

40 15. In a grinding machine having a longitudinally traversable work table, means including a reversible electric motor to traverse said table longitudinally in either direction, a reversing switch therefor, a two-speed gear mechanism including a clutch which is interposed between the table and said motor, a single control lever which is arranged for movement in two directions, connections between said lever and clutch whereby movement of the lever in one direction serves to actuate said clutch, and connections between said lever and the reversing switch to control the direction of movement of said table.

45 16. In a grinding machine having a transversely movable rotatable grinding wheel and a slide therefor, means including a reversible electric motor to traverse said slide transversely in either direction, a reversing switch therefor, a longitudinally movable work supporting table, means including a reversible electric motor to traverse said table longitudinally in either direction, a reversing switch therefor, a control lever which is slidable vertically and pivotally mounted, connections between said lever and said second reversing switch whereby movement of the control lever about its pivot serves to control the direction of movement of said supporting table, and connections between said lever and said first reversing switch which are rendered effective when the control lever is moved vertically and rotated to control the forward and rearward movement of said wheel slide.

50 17. In a grinding machine having a transversely movable rotatable grinding wheel and a slide therefor, means including a reversible elec-

tric motor to traverse said slide transversely in either direction, a reversing switch therefor, a longitudinally traversable work supporting table, means including a reversible electric motor to traverse the table longitudinally in either direction, a reversing switch therefor, a two-speed gear mechanism including a clutch which is interposed between the work supporting table and said second motor, a single control lever which is slidable vertically, rotatable and pivotally mounted so as to swing in two directions, connections between said lever and clutch whereby pivotal move-

ment of said lever in one direction serves to actuate said clutch, connections between said lever and the second reversing switch whereby pivotal movement of said control lever in a second direction serves to control the direction of movement of said table, and connections between said lever and the first reversing switch which are rendered effective when said control lever is moved vertically to control the forward and rearward movement of said wheel slide. 5 10
